UNITED STATES PATENT OFFICE.

ELWOOD P. HORMEL, OF SURPRISE, NEBRASKA.

SHOE-CLOSURE.

1,249,092.

Specification of Letters Patent.

Patented Dec. 4, 1917.

Application filed March 21, 1917. Serial No. 156,387.

To all whom it may concern:

Be it known that I, ELWOOD P. HORMEL, a citizen of the United States, residing at Surprise, in the county of Butler and State 5 of Nebraska, have invented certain new and useful Improvements in Shoe-Closures; and I do hereby declare the following to be a full, clear, and exact description of the invention, such as will enable others skilled in 10 the art to which it appertains to make and use the same.

This invention relates to improvements in shoe closures.

The object of this invention is the provision of a shoe closure especially adapted and constructed to be applied to shoes so that the use of laces, eyelets or other lacing means may be eliminated.

A further object of this invention is the 20 provision of a closure of novel construction, especially adapted to be applied to the upper of a shoe of any construction and is so arranged thereon as to draw the meeting edges of the upper in toward one another 25 fastening the shoe to the foot of the wearer.

A further object of this invention is the provision of a shoe closure which embodies in its construction, a pair of members, each formed of a single piece of metal having a 30 hinged attaching end, which attaching end is secured to the upper of the shoe adjacent the meeting edges thereof, one of the members provided with spaced longitudinally extending key-hole openings, while the opposite member is provided with a stud to 35 removably fit within the key-hole openings for holding the shoe upper closed about the foot of the wearer, and the member carrying the key-hole openings is provided on its side 40 edges with longitudinally extending right angularly arranged side flanges, which are adapted to engage the opposite side longitudinal edges of the other member holding the same against lateral shifting movement 45 when in fastened position.

A still further object of this invention is the provision of a shoe closure of this character, which will be simple, durable and efficient, and which may be manufactured and 50 sold at a comparatively low cost.

With these and other objects in view as will become more apparent as the description proceeds, the invention consists of the novel combination and arrangement of parts

hereinafter more fully described and set forth in the claims hereto appended.

In the drawing:

Figure 1 is a front elevation illustrating my improved closure applied to a fragment of an upper of an ordinary shoe,

Fig. 2 is a horizontal sectional view of the same,

Fig. 3 is a perspective view of one of the members,

Fig. 4 is a perspective view of the other member.

Like numerals of reference designate corresponding parts in all the figures of the drawing.

Referring more particularly to the drawing, the numeral 1 indicates a fragmentary portion of an upper of an ordinary type of shoe and has secured thereto, my improved shoe closure designated in its entirety by the 70 numeral 2.

My improved shoe closure comprises the members 3 and 4, each member provided at one end with a hinged attaching member, which is adapted to be secured to the upper of the shoe adjacent the meeting edges 80 thereof.

The member 3 comprises in its construction, the relatively long narrow rectangular body 5, which is provided at one end with a turn-back portion 6, constituting a hinged 85 barrel.

An attaching member 7 comprises a semi-circular body which has one end extended to provide a hinged barrel 8, which co-operates with the hinged barrel 6 of the member 3 90 and is adapted to be hingedly connected thereto by a pin 8', which extends transversely through the barrels 6 and 8 connecting the member 7 to one end of the member 3.

The attaching member 7 is provided on its periphery with the spaced outwardly extending fastening prongs 9, which are adapted to be embedded in the upper of the shoe for positioning the member 3 on the 100 outer side thereof so that the same may extend beyond the edge of the upper of the shoe.

The body 5 is provided on its upper side adjacent its free end centrally of its side 105 longitudinal edges with the vertical stud 10, which has an enlarged head 11 which head extends laterally beyond the plane of the

stud 10, the purpose of which will be hereinafter more fully described.

- The member 4 comprises in its construction a relatively long rectangular body 12, 5 which has its opposite side longitudinal edges bent downwardly at right angles thereto to define guide flanges 13; one end of the body 12, is reduced and bent back upon itself to provide a hinged barrel 14, 10 which is adapted to coöperate with the barrel 15 of the attaching member 16, which attaching member 16 is identical in construction with the attaching member 7 of the member 3.
- 15 The barrel 15 is hingedly connected to the barrel 14 by a transversely extending pin 17, which is arranged through the barrels 14 and 15, hingedly connecting the member 16 with the member 4.
- 20 The member 16 is provided on its periphery with the spaced outwardly extending fastening prongs 18, which are adapted to be embedded in the upper of the shoe positioning the member 4 on the exterior thereof 25 so that it will extend beyond the edge of the upper of the shoe and in the direction of the member 3.

The body 12 of the member 4 is provided with the spaced longitudinally extending 30 key-hole openings 19, which have their enlarged portions 20 extending in the direction of the attaching members 16, thus it can be seen that when the member 4 is arranged over the member 3, the stud may be inserted 35 in the enlarged portions 20 of the key-hole openings 19 and forcing said pin back into the constricted portions locating the head on the upper surface of the body 12, thus securely holding the shoe about the foot of 40 the wearer.

The body portions and attaching members of each of the members 3 and 4 are formed of any suitable metal, suitable for the purpose, and each have one end reduced and 45 bent back upon itself to provide a hinged barrel, which coöperates with the reduced portions of the attaching members which have a hinged barrel, hingedly connecting the attaching members to their body portion.

The attaching prongs of the members 7 and 16 of the members 3 and 4 are bent downwardly and embedded in the upper of the shoe as at 21, the member 3 is located on 55 the left side and the member 4 is located on the right side of the upper of the shoe, the member 3 is then extended transversely across the meeting edges of the upper, the member 4 is adapted to be bent downwardly 60 at its hinged point and embraced over the member 3, thus positioning the body 5 of the member 3 inwardly between the side flanges 13 of the member 4, locating the stud in the constricted portions of the openings 19, and 65 the device is assembled on the foot of the

wearer and held against displacement therefrom, it being understood that the flanges 13 prevent lateral or vertical movement of the member 3 in either direction.

What is claimed is:

1. A shoe closure comprising a pair of members having rectangular body portions, hinged attaching members connected to one end of each of the body portions of each member, fastening prongs carried by the attaching members, a stud carried by the body of one of said members, the body of the other of said members provided with key-hole slots to detachably receive the stud for securing the members one to the other, as and for the purpose specified. 70

2. A shoe closure comprising a pair of members constructed of metal and each comprising a rectangular body, one of said members having its opposite side longitudinal edges bent downwardly at right angles thereto providing guide flanges, said body provided with longitudinally extending spaced key-hole openings, one end of said body being reduced and bent back upon itself 85 to provide a hinged barrel, an attaching member, spaced prongs formed on the periphery of said attaching member, one end of said attaching member reduced and bent back upon itself to provide a barrel hingedly connecting it to the barrel of the body, the other of said members provided on its upper side adjacent one end and centrally of its side longitudinal edges with a stud having an enlarged head, one end of said body bent 90 back upon itself to provide a hinged barrel, an attaching member hingedly connected to the barrel and provided on its periphery with spaced attaching prongs, said stud adapted to be detachably fitted within one of 100 the key-hole openings of the body of the other member and locating its body between the guide flanges of said member preventing laterally shifting movement of the members with relation to one another. 105

3. A shoe closure comprising a pair of members, attaching plates hingedly connected to one end of each of the members, prongs carried by the attaching plates, means formed on the side edges of one of the members for embracing the other of said members for holding the same against lateral shifting movement, and means carried by one of said members and detachably connected to the other of said members for holding the members detachably connected together, said prongs on the attaching plates adapted to be embedded in a support, as and for the purpose specified. 110

4. A shoe closure comprising a pair of 125 members each consisting of a rectangular body portion, attaching plates, said attaching plates being hingedly connected to one end of the body of each of the members, prongs, said prongs formed on the periph- 130

ery of each of the attaching plates at a relatively spaced distance apart to facilitate the embedding of the attaching plates to the upper of the shoe, studs formed on the upper side of one of the body portions, guide flanges carried by the other body portion, one of said body portions provided with a key-hole slot arranged longitudinally therein and being adapted to detachably receive the stud of the other member to permit

the sides of the member to be adjustably connected together for fastening the shoe about the ankle or foot of the wearer.

In testimony whereof I affix my signature in presence of two witnesses.

ELWOOD P. HORMEL.
